UNITED STATES PATENT OFFICE

LLOYD E. MILLER, OF CLEVELAND HEIGHTS, OHIO, ASSIGNOR TO THE RELIANCE ELECTRIC AND ENGINEERING COMPANY, OF CLEVELAND, OHIO, A CORPORATION OF OHIO

CONTROL MEANS FOR SHEET FEEDING OR DELIVERING, OR THE LIKE

Application filed July 30, 1930. Serial No. 471,725.

This invention relates to controls for sheet feeding or delivering, or the like where desired conditions of speed or tension are to be had; and it is among the objects of the invention to provide a construction which can afford accurate control to speed or tension as may be required and without undue complication of the machines involved. Other objects and advantages will appear as the description proceeds.

To the accomplishment of the foregoing and related ends, the invention, then, consists of the features hereinafter fully described, and particularly pointed out in the claims, the following description and the annexed drawing setting forth in detail certain embodiments of the invention, such being illustrative however of but a few of the various ways in which the principle of the invention may be employed.

In said annexed drawing:—

Fig. 1 is a diagrammatic view showing one embodiment of the invention; Fig. 2 is a similar view of another form; and Fig. 3 is a fragmentary sectional view showing a detail of the construction of the control motor.

Referring to Fig. 1 of the drawing, there is indicated a moving surface, in the form of a roll R, and which forms a part of a roll assembly such for instance as for the handling of sheet material. In such a construction, the material in sheet or web form may be handled as desired, as for instance on a wind-up roll, or by a pinch-roll functioning of the mechanism or as a trough-roll arrangement, as the case may be. Connected mechanically is an electromagnetic rotor 2, which may be the armature of a driving motor for the roll, or a generator acting as a brake on the roll.

In the case for instance where sheet material, such for example as a web of paper, textile, metal or the like is being forwarded on the roll positively driven, the rotor 2 is an armature arranged to recurve current from a generator G, and has associated a field 3 supplied by current from the line 4, connected to any suitable source of D. C. In the armature circuit is a control motive device energized in such circuit. If in the form of a motor, as illustrated with armature 5, the windings

may be such as to preferably provide a low torque, and the associated field 6 may be supplied with current by leads 7. Acting upon the control motor 5 is a means tending to move such motor counterwise, or in a direction opposite to that normally engendered by the energizing current. In one form, such counter means may be gravitational, and as shown in Fig. 1 this may comprise a weight 8 of proportion to just normally balance the torque imparted by the desired energizing current. Such weight may be arranged to act leverwise upon the control motor shaft, as by a pulley 9, or equivalent, the weight being suspended for example from one end of a cable 10 and the other end of the cable being wound upon the pulley.

Arranged to be operated by the control motive device 5 is a means regulating the driving motor, preferably by controlling the generator G, through its field 11 by a variable resistance 12. Such variable resistance may be actuated directly with a coupling to the motor shaft 13, or convenient intermediary drive may be applied as desired, as long as the resistance is operated in definite relation with the motive device 5. In order to prevent possible overrun of the control motor 5, and thereby an excessive change in the rheostat arm controlling the field 11, I apply a damping means. In the form shown in Fig. 1, this is of a mechanical character, and while a mechanical escape movement or a brake may be employed, preferably I employ a dashpot D. Instead of or in addition to mechanical damping means however, I also contemplate the employment of an electrical damping means, as embodying a preferable construction, and as will be referred to more in detail hereinafter.

With such a construction, it will be seen that sheet material, for instance a web of paper may be handled onto the roll R, the armature 2 of the driving motor determining the speed thereof. The armature 5 of the control motor being energized in the armature circuit of the driving motor tends to turn, but the counter force of the weight 8 being in this state exactly equal and opposite, no movement of the motor shaft 13 results.

Fine adjustment to the desired condition may be had by a rheostat 14 in the field 7 of such motor. If now, the tension on the material varies, for instance in the direction of an increase and the load correspondingly tends to increase current in armature 2, armature 5 also has its balance disturbed with respect to the counterweight, and a differential of movement results in the shaft 13, thereby operating the variable resistance 12, and the generator voltage is diminished to bring the driving motor to required condition.

In the form shown in Fig. 2, a moving surface, such as a roll R', which forms a part of a roll assemblage, as a forwarding roll or pinch rolls or trough rolls, such for instance as a wind-up roll for the handling of sheet material, is mounted with an electro-magnetic rotor 2', which may be the armature of a driving motor for the roll, or a generator acting as a brake on the roll. In association with the rotor is a field 3' supplied by current from the line 4'. In the circuit with the rotor 2' is the armature 5' of a control motor whose field 6' is supplied through leads 7' from a suitable line source. In one of such leads, an adjusting rheostat 14' is desirably included. One of the leads, 15, to the field 3' is provided with a rheostat 12', whose controller-arm *a* is carried by a shaft coupled to the motor 5'. Similarly to the construction above described, there is also applied in connection with such shaft a means for tending to move the control motor counterwise, this preferably taking the form here of a counter-torque motor 8', such for instance as a D. C. shunt wound motor of low current capacity, which is stalled across the line and acts like the constant pull of the weight above described (but assumed in Fig. 2 to be in a clockwise direction), the motor current being held to a low value by the internal resistance of the motor or by the combination of the internal resistance and an external resistance 16 in series with the motor armature. The desired amount of torque can be had by regulating the external resistance.

With this construction, as will be readily understood, with the feed of material at a certain speed onto a build-up roll for instance, and the rotor 2' acting as an armature, and thereby producing the proper tension on the material on the roll R', such winding tension is maintained until a change in the conditions occurs. If now due to the building up the tension be increased, this would increase the work done by the motor 2', and the relation between the control motor 5' and the counter-torque motor 8' is then upset, such that the differential of action between the control motor and its counter-balance motor operates to adjust the rheostat 12' to bring the current to proper requirements to again correlate the roll R' to requirements. In such manner, a constant tension may be

had. Again, where desired, a constant rate of feed may be maintained.

Similarly, if a web of paper or other material is being delivered off of roll R' and the armature 2' is a braking armature, and it is desired to maintain a constant tension, the setting of rheostat 14' will have been primarily adjusted to fix the balance at that tension. If then the tension tends to vary, as for instance with diminishing diameter of an unwinding roll, the armature 5' will be correspondingly influenced, and its balance with the counter-torque means 8' will be destroyed, and a differential of movement will result in the shaft 13', operating the variable resistance 12' to restore conditions in the braking generator 2'. When the machine 2' is acting as a braking generator, it may be connected into any suitable load circuit.

In order to prevent possible overrun of the control motor 5', mechanical braking or damping devices may be employed, as referred to in connection with Fig. 1. Preferably however, as before indicated, an electromagnetic damping means is employed in substitution of or in addition to the mechanical damping means. For this, the armature of the control motor is provided with a cylindrical member 17 of copper or other highly conductive metal (see Fig. 3), surrounding the armature and being carried thereby outside of the windings *w*. As the armature is rotated, E. M. F. will be generated in the band 17, and circulating currents will flow therein, producing a torque resisting the rotation. The E. M. F. so introduced, and the resultant torque is proportional to the speed of the motor. With suitably proportioned windings of the armature, the torque tending to produce motion can be large as compared to the torque tending to resist motion at a low speed. Since the torque tending to produce motion remains the same regardless of speed, and the torque tending to resist motion varies directly with the speed, the opposing torques may be then such as to tend to become equal before an undesirably high speed and an overrun is attained, and correspondingly a damping action against such overrun is had. With such means, the sensitivity of the control motor is in no way interfered with, and a higher sensitivity is available than in the case of mere mechanical damping means, since the latter incur considerable frictional losses. Either control motor 5 or 5' may, of course, be so equipped.

In accordance with the invention, control may thus be had for linear speed or for tension in the sheet material as handled on the rolls, as may be desired; and the construction while advantageous in the handling of sheet material, cloth, metal, etc., on which a constant lineal speed is being maintained from some outside source, and on which a constant tension is desired, in being forwarded or col-

lected, or fed out, is particularly advantageous with paper, since any desired rate either of lineal speed or of tension may be adjusted for, and may be maintained, notwithstanding such otherwise disturbing conditions as variations in rate from decreasing or increasing diameter in the case of feeding in roll form, or tendencies to vary the speed or tension as imposed by other mechanism beyond the device here directly concerned.

This application is a continuation in part of my application Ser. No. 432,613 filed March 3, 1930.

Other modes of applying the principle of the invention may be employed, change being made as regards the details described, provided the means stated in any of the following claims, or the equivalent of such, be employed.

20 I therefore particularly point out and distinctly claim as my invention:—

1. In apparatus of the character described, a roll assembly for handling sheet material, a driving motor therefor, a generator supplying E. M. F. to said driving motor, a control motor energized in the armature circuit of said driving motor and said generator, a weight, a cable suspending said weight at one end and having its other end wound on a pulley secured to the control motor shaft to counter the normal moving tendency thereof, means for preventing overrun of said control motor, said means including a closed-circuit band about the armature of said motor, and a variable resistance in the field circuit of said generator also operated by said control motor shaft.

2. In apparatus of the character described, a roll assembly for handling sheet material, a driving motor therefor, means for supplying current for said driving motor, a control motor energized in the armature circuit of said driving motor, a counter-torque motor connected to the control motor shaft to counter the normal moving tendency thereof, means for regulating said counter-torque motor, a variable resistance in the field circuit of said driving motor also operated by said control motor shaft, and means for preventing over-run of said control motor.

3. In apparatus of the character described, a roll assembly for handling sheet material, a driving motor therefor, a generator supplying current for said driving motor, a control motor energized in the armature circuit of said driving motor, a counter-torque motor tending to turn said control motor shaft in an opposite direction, and a variable resistance in the field circuit of said generator operated by the movement of said control motor.

4. In apparatus of the character described, a roll assembly for handling sheet material, a driving motor therefor, a control motor energized in the armature circuit of said

driving motor, a counter-torque motor tending to turn said control motor in the opposite direction, means for preventing overrun of said control motor, and means operated by the movement in said control motor to regulate said driving motor.

5. In apparatus of the character described, a roll assembly for handling sheet material, a driving motor therefor, a rotatable control motor energized in the armature circuit of said driving motor, gravitational means tending to move said control motor counter-clockwise, and means operated by the movement in said control motor to regulate said driving motor.

6. In apparatus of the character described, a roll assembly for handling sheet material, an electromagnetic rotor connected therewith, a control motor energized to the circuit of said electromagnetic rotor, a counter-torque motor tending to turn said control motor oppositely, means for preventing overrun of said control motor, and means operated by the movement in said control motor to regulate said electromagnetic rotor.

7. In apparatus of the character described, a roll assembly for handling sheet material, an electromagnetic rotor connected therewith, a rotatable control motor energized in the circuit of said electromagnetic rotor, a counterweight tending to turn said control motor oppositely, and means operated by the movement in said control motor to regulate said electromagnetic rotor.

8. In apparatus of the character described, a roll assembly for handling sheet material, an electromagnetic rotor connected therewith, a control motor energized in the circuit of said electromagnetic rotor, means tending to move said control motor counter-clockwise, means for preventing overrun of said control motor, said means including a closed circuit band about the armature of said motor, and means operated by the movement in said control motor to regulate said electromagnetic rotor.

9. In apparatus of the character described, a roll assembly for handling sheet material, an electromagnetic rotor connected therewith, a control motor energized in the circuit of said electromagnetic rotor, gravitational means tending to move said control motor counter-clockwise, means for preventing overrun of said control motor, and means operated by the movement in said control motor to regulate said electromagnetic rotor.

10. In apparatus of the character described, a roll assembly for handling sheet material, an electromagnetic rotor connected therewith, a rotatable control motor energized in the circuit of said electromagnetic rotor, counter-torque means tending to move said control motor counter-clockwise, and means operated by the movement in said control motor to regulate said electromagnetic rotor.

11. In apparatus of the character de-

- scribed, a roll assembly for handling sheet material, an electromagnetic rotor connected therewith, a control motor energized in the circuit of said electromagnetic rotor, means tending to move said control motor counterwise, means for preventing overrun of said control motor, and means operated by the movement in said control motor to regulate said electromagnetic rotor.
10. 12. In apparatus of the character described, a roll assembly for handling sheet material, an electromagnetic rotor connected therewith, a rotatable control motor energized in the circuit of said electromagnetic rotor, means tending to move said control motor counterwise, and means operated by the movement in said control motor to regulate said electromagnetic rotor.
15. 13. In apparatus of the character described, a driven machine, a driving motor connected therewith, a control motor energized in the armature circuit of said driving motor, means tending to move said control motor counterwise, means for preventing overrun of said control motor, said means including a closed-circuit band about the armature of said motor, and means operated by the movement in said control motor to regulate said driving motor.
20. 14. In apparatus of the character described, a driven machine, an electromagnetic rotor connected therewith, a control motor energized in the circuit of said electromagnetic rotor, means tending to move said control motor counterwise, means for preventing overrun of said control motor, said means including a closed-circuit band about the armature of said motor, and means operated by the movement in said control motor to regulate said driving motor.
25. 15. In apparatus of the character described, a driven machine, an electromagnetic rotor connected therewith, a control motor energized in the circuit of said electromagnetic rotor, a counterweight tending to turn said control motor oppositely, damping means for preventing overrun of said control motor, and means operated by a movement in said control motor to regulate said electromagnetic rotor.
30. 16. In apparatus of the character described, a driven machine, an electromagnetic rotor connected therewith, a control motor energized in the circuit of said electromagnetic rotor, means tending to move said control motor counterwise, damping means for preventing overrun of said control motor, and means operated by the movement in said control motor to regulate said electromagnetic rotor.
35. 17. In apparatus of the character described, a driven machine, a driving motor connected therewith, a rotatable control motor energized in the circuit of said driving motor, a counter-torque motor tending to
- turn said control motor oppositely, and means operated by the movement in said control motor to regulate said driving motor.
40. 18. In apparatus of the character described, a driven machine, a driving motor connected therewith, a rotatable control motor energized in the armature circuit of said driving motor, means tending to move said control motor counterwise, and means operated by the movement in said control motor to regulate said driving motor.
45. 19. In apparatus of the character described, a driven machine, an electromagnetic rotor connected therewith, a rotatable control motor energized in the circuit of said electromagnetic rotor, a counter-torque motor tending to turn said control motor oppositely, and means operated by a movement in said control motor to regulate said electromagnetic rotor.
50. 20. In apparatus of the character described, a driven machine, an electromagnetic rotor connected therewith, a rotatable control motor energized in the circuit of said electromagnetic rotor, means tending to move said control motor counterwise, and means operated by the movement in said control motor to regulate said electromagnetic rotor.
